JOHN WILDE, DANIEL WILDE, AND JOHN H. WILDE, OF WASHINGTON,
IOWA.

Letters Patent No. 74,652, dated February 18, 1868.

IMPROVEMENT IN CORNSTALK-CUTTERS PREPARATORY TO PLOUGHING.

The Schedule referred to in these Letters Patent and making part of the same.

TO ALL WHOM IT MAY CONCERN:

Be it known that we, JOHN WILDE, DANIEL WILDE, and JOHN H. WILDE, of Washington, in the State of Iowa, have invented a certain new and useful Improvement on Cornstalk-Cutters; and we do hereby declare that the following is a full, clear, and exact description of the same, reference being had to the accompanying drawings, and the marks and letters thereon, which said drawings form part of this specification, and show a cornstalk-cutter constructed under our invention—

Figure 1 thereof being a top view, and

Figure 2 a side view, the two different positions of the cutter-cylinder and frames being indicated by the two different colors.

In both of these figures like marks and letters are used to indicate like parts.

In this machine, the frame *a*, to which the cutter-cylinder is attached, marked *b*, is the main frame, and has the tongue *c* connected to it, so that the draught is direct on the cutter-cylinder frame, while the wheel-frame *d* is the secondary frame. This secondary frame *d* is connected to the main frame *a* by pivot at *e*, and has the driver's seat at *f*. There is attached to the main frame, at *g*, by pivot, a treadle-frame, *h*, having a foot-board, *i*. This treadle-frame is connected also to the secondary frame *d* by chains, cords, or rods *j*. A lifting-iron, *k*, is affixed to the treadle-frame, and passes through an eye, *l*, fitted in the axle *m*. This iron, *k*, is toothed, as is shown by fig. 2, so that it will act as a catch to hold up the main frame and cutter-wheel. By putting the foot on the foot-board *i*, and pressing downward, the treadle-frame will act as a lever upon the main frame, and raise that frame and the cutter-cylinder. At any time, therefore, when it is desirable to elevate the cutter-cylinder from the ground, it can easily be accomplished by the pressure of the foot upon the board *i*.

The operation of this machine, from this description of its construction, will readily be understood, and by virtue of the arrangement of the frames and the tongue, and the making the draught direct upon the cutter-cylinder frame, the efficiency of the machine is greatly increased. Suitable means or devices can be attached to the front end of the main frame or wheel-frame for turning down the stalks into the track of the cutter-cylinder.

What we claim as our invention, and desire to secure by Letters Patent, is—

1. The arrangement of the main frame with the cutter-cylinder and tongue and the wheel-frame, as herein recited.
2. We claim combining, with the main frame and the wheel-frame, the treadle-frame, as and for the purposes herein set forth.

This specification signed, this 14th day of December, 1867.

JOHN WILDE,
DANIEL WILDE,
JOHN H. WILDE.
